Primary Examiner — Marissa J. Cash*Assistant Examiner* — Earl B Elowsky(74) *Attorney, Agent, or Firm* — JCIPRNET(57) **CLAIM**

The ornamental design for a fluid distribution valve as shown and described.

DESCRIPTION

FIG. 1 is a first perspective view of a fluid distribution valve showing our new design;

FIG. 2 is a second perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is an enlarged perspective view of the area encircled in FIG. 1.

The broken lines in FIGS. 1-4 and 7-9 are for the purpose of illustrating portions of the fluid distribution valve that form no part of the claimed design. The dot-dash broken lines in FIGS. 1 and 9 are for annotating the enlarged views only and form no part thereof.
